(57) **CLAIM**

The ornamental design for an end piece for a bench, as shown and described.

DESCRIPTION

FIG. 1 is a perspective view of an end piece for a bench, in accordance with the present design;

FIG. 2 is a left side view of the end piece for a bench shown in FIG. 1;

FIG. 3 is a right side view of the end piece for a bench shown in FIG. 1;

FIG. 4 is a rear side view of the end piece for a bench shown in FIG. 1;

FIG. 5 is a front side view of the end piece for a bench shown in FIG. 1;

FIG. 6 is a top side view of the end piece for a bench shown in FIG. 1;

FIG. 7 is a bottom side view of the end piece for a bench shown in FIG. 1; and,

FIG. 8 is a perspective view of the end piece for a bench shown in FIG. 1 being depicted as a component of a bench. The broken lines in FIG. 8 illustrating the other components of a bench depict environmental subject matter that forms no part of the claimed design.

1 Claim, 6 Drawing Sheets
